LAKE H. SPRINKLE, OF BROOKLYN, NEW YORK.

APPARATUS FOR MAKING PLATES FOR ARTIFICIAL TEETH.

1,206,478.

Specification of Letters Patent. Patented Nov. 28, 1916.

Application filed January 6, 1916. Serial No. 70,614.

To all whom it may concern:

Be it known that I, LAKE H. SPRINKLE, a citizen of the United States, residing at Brooklyn, in the county of Kings and State of New York, have invented certain new and useful Improvements in Apparatus for Making Plates for Artificial Teeth, of which the following is a specification.

I have invented certain improvements in connection with the making of plates commonly used for supporting artificial teeth in the human mouth; and particularly an apparatus for casting said mouth plates in a manner that both avoids waste and loss and at the same time results in a very superior product.

A most important object of my invention is to provide a construction whereby the mold in which such mouth plates are formed can be conveniently and quickly inspected and cleaned as soon as it is in condition to be used; whereby any foreign particles can readily be removed and all danger of marring or ruining the plate entirely obviated; and a further object is to enable the mold to be more easily handled than heretofore, and greater efficiency and despatch secured in operation.

The above and other objects and advantages of my invention will appear from the following description, taken in connection with the accompanying drawings, and be precisely defined in the appended claims.

I wish to have it understood, however, that the disclosure herein sets forth but one embodiment of my inventive idea; and that changes in the structure actually shown may be made within the meaning of the terms in which the claims are expressed. In other words, differences in the phrasing of the claims are intended to cover actual modifications in the details of my invention that I may find it advisable to adopt; provided of course that such modifications fall within the scope and spirit of my invention as the claims specify the same.

On said drawings: Figure 1 is a plan view showing a plaster impression or pattern of the roof of a human mouth for which a plate is desired; this pattern giving the model for the mold-flask. Fig. 2 is a longitudinal section of a portion of a mold flask used in the practice of my invention; Fig.

3 is a sectional view showing such a mold flask just before closing, the model being inside; Fig. 4 is a sectional view of such a flask closed up before the formation of the mold-cavity; Fig. 5 is a similar view showing the finished mold therein; Fig. 6 is a section showing the mold-containing flask disposed in a receiving flask for the operation of casting; Fig. 7 is an elevation of the mold-containing flask illustrating the entrance to the mold cavity; and Fig. 8 is a similar view of the flask seen from the opposite end. 55 60 65

The same numbers indicate the same parts on all the views.

In the manufacture of mouth plates it has previously been the custom to begin with an exact pattern, generally of plaster, 70 having a specially formed surface corresponding to the interior of an individual mouth for which a plate is to be produced. Such a pattern is shown at 1 in Fig. 1. If the plate is to fit the roof of the mouth, the 75 surface 2 of the pattern 1 will be shaped by putting a mass of soft plaster on an implement 3, and forcing the mass against the roof of the mouth to receive a true imprint thereof. The plaster is then removed, set 80 up and a reproduction of the surface 2 is made by covering the pattern 1 with plaster, or the like and thereby forming the model 1'; Figs. 2, 3, 4 and 5; which goes into the mold flask. The surface 2' of this 85 model will correspond exactly to the surface 2, only it will be convex where the first surface was concave and vice versa. After the model is separated from the pattern; its surface 2' is given a coating, as of 90 wax 4. The model with its wax coating is then embedded in a plastic mold of any suitable composition which is packed into a suitable flask or casing, an aperture leading to the wax of course being present to 95 enable the wax to be removed. When the mold has set it is heated, so that the wax melts and can be poured out. In consequence a mold-cavity is left in the plastic of such description as to form a plate of 100 the necessary thickness and contour when molten material is poured into it.

This process has a number of drawbacks, chief among which is the impossibility of making sure that the mold is perfect before 105 utilizing it in the usual way. The mold

cavity is very small and narrow so that it can neither be examined throughout, nor relieved of any extraneous substances that may be inside of it. Therefore the wax, especially if not entirely pure, will frequently leave dirt in the mold-cavity; and in such a case the plate will be a very poor one. In fact, plates made by this method are nearly always marked or rough, and as many as 10 ten per cent. will be so defective as to be totally useless. Further likelihood of injury to the plates is also encountered after the casting is finished and the plate taken out. This stage requires that the mold, 15 which has now become hard, be broken up till the plate is freed from the plaster, and damage to the plate when the plaster is being shattered, can easily take place. Further, such a mold can be used but once. 20 In my invention I avoid the disadvantages above mentioned by using a mold-containing flask 5, comprising a pan-shaped section 6 with rim 7, a ring-shaped section 8, and a third section 9; so arranged that the flask 25 can not only be taken apart to allow the mold-cavity to be examined and wiped out, if need be, but also manipulated and moved about, when closed up, by the operator; and opened when the plate is finished and ready 30 to be extracted, without any risk whatever. With this flask a mold can be used several times.

The section 8 has the same contour as the rim 7, and has fingers or projections 10 to 35 receive the rim and enable the rim and the section 8 to be fitted, edge to edge, together; and the section 9 has similar projections to engage the section 8. Further, the rim 7 and the section 8 will have recesses 11, which 40 register, when the flask is made up, to make a relatively large aperture, leading to the mold-cavity, as clearly seen in Fig. 7. Of course suitable recesses may be provided to receive the projections 10.

45 I use the flask, for example, by taking the section 9 as the bottom and placing thereon the section 8, and then filling with plastic substance, such as plaster, as shown in Fig. 2. The model 1' with wax coating 4 on its special surface 2', is then placed on the top of the plaster, preparatory to covering it entirely. The model may be laid so that the surface 2' and wax coating 4 may be up or down, as the result in either 55 case will be the same. Then the pan-shaped section 6 is filled with plaster, and placed on over the model 1', the rim 7 fitting upon the section 8, and being centered by the projections 10. In order to allow of the flask 60 being opened and the mold divided after the plaster has hardened, I give the top of the plaster inclosed by the ring-shaped section 8 adjacent the upper edge of the section, a coating of shellac or soap or other

suitable non-adhesive substance, as indicated 65 by the numeral 12; and this expedient will enable the plaster in the pan-shaped section 6 to be separated from the plaster in the section 8 after the mold has set. Fig. 3 shows the pen-shaped section about to close 70 over the pattern and embed the same in the mold completely.

When the flask is closed the sections will fit tightly together as indicated in Fig. 4; the fingers or projections 10 retaining the sections in true relative positions. Enough of the plaster will be removed from the aperture furnished by the recesses 11 to expose the edge of the wax, and when the plastic has set, the flask with the mold therein can 80 be heated enough to melt the wax and the latter caused to pour out through the hole in question; whereby the mold-cavity will be created.

My method of producing mouth plates has 85 now reached the stage when the flask can be opened in order to inspect the mold-cavity; and the pan-shaped section 6 is separated from the sections 8 and 9 which remain together. The plaster in the section 6 90 separates easily from the rest of the plaster because of the shellac, and both the top and bottom of the mold-cavity can be carefully looked over and any dirt or other foreign matter in this cavity can be easily gotten 95 rid of. The flask is now closed by again pressing the sections together, and the molten material can now be poured into the mold-cavity through the large aperture leading to the same. Fig. 5 indicates the manner in 100 which the mold can be opened for the above purpose.

The wax may be removed from the investment material in the sections 6 and 8 in any way that will thoroughly clean the mold. 105

In order to effect the casting, the flask 5 is supported with the aperture leading to the mold-cavity on top and this aperture will receive enough molten material, such as aluminum, to fill the mold-cavity. Before pouring the aluminum into the aperture the flask 5 is placed into a larger flask 13, which loosely and snugly receives it, as shown in Fig. 6; and compressed air or some other pressure agent will be employed to force the 110 molten aluminum into the mold-cavity before it solidifies. As shown in Fig. 6, the flask 13 is open at both ends, the upper end being enlarged, and is in effect approximately funnel-shaped; so that the flask 5, 115 which tapers from top to bottom, can rest in contact with the inside of the flask 13, snugly fitting the same and secured in proper position thereby. The large end of the flask 13 will receive a cover provided with suitable packing, to make it tight, and through this cover leads a conduit by which the pressure agent is supplied. The air impels the 120

molten aluminum down into the cavity, and inasmuch as the mold is more or less porous any air which passes to the inside of the flask 5 can escape therefrom between the 5 sections and through the exit openings 14 in the section 6 and section 9. If desired, registering recesses may be provided in the rim 7 and section 8 in order to increase the 10 number of exit openings, as shown in Fig. 8. After the aluminum fills the mold-cavity the 15 closed flask 5 is removed from the flask 13 and taken apart, and the casting is finished. It is understood of course that the compressed air issuing from the flask 5 will escape through the bottom of the flask 13; as 20 this flask rests upon a perforated support.

The flask 5 will of course be of such size that it will fit the flask 13 with the flat outer faces of the sections 6 and 9 close to 25 the inner surfaces of the flat sides of the outer flask. I make the sections of the flask 5 so that they will hold together with sufficient tightness by reason of the fingers 10; but additional means to produce this 30 effect may be employed if needed. If desired, suitable means may also be employed to prevent too much compressed air from passing between the flat faces of the flask 5 and the flask 13; so as to make sure that 35 the molten material may be properly forced into the mold cavity.

By means of my invention a mold is very easily handled, and can be put into the flask 13 and taken out with practically no 40 effort whatever. Furthermore, the plastic mold does not have to be broken up by force after the casting operation is finished; and, owing to the accessibility of the mold-cavity, the possibility of dirt therein spoiling 45 the casting is entirely eliminated. Actual experiments have demonstrated that not more than two per cent. of castings made by my process and apparatus are defective under any circumstances; and if the operator 50 is ordinarily careful the spoiling of a plate will be a very rare occurrence. Furthermore by locating the exit openings at various points with respect to the mold-cavity, the compressed air tends to distribute 55 the molten material more evenly in the mold-cavity, and this fact likewise helps to increase the value and practical merit of my invention by insuring a high grade output. After the first plate is finished the 60 mold can be used over to make a number of additional plates, and is not by any means limited to a single plate like molds made by the old method, which require to be broken and thus destroyed before the plate can be 65 taken out. Of course the flask 5 can also be used by taking the section 6 first to receive the pattern 1, and then placing the sections 8 and 9 on top of it. When the section 6 is filled and the pattern in posi-

tion, the section 8 is added and filled till the 65 pattern is covered, and the flask closed by placing the section 9 on the section 8 as a lid or cover. This way is often a good deal easier and more practical:

My invention enables me to cast plates of 70 aluminum, gold or other metal for either the roof of the mouth or the lower jaw; and either a forced blast, such as a medium under pressure, or a suction blast can be utilized to impel the molten material into 75 the mold cavity. Other methods of forcing the molten material into the mold cavity may of course be resorted to.

The flask 5 may also be carried in a centrifugal machine, and centrifugal force instead of a pressure agent utilized to make 80 sure of filling the mold-cavity.

Any suitable plastic composition may be 85 employed in the mold, as will be understood.

Having described my invention, what I believe to be new and desire to secure and protect by Letters Patent of the United States is:

1. The combination with a flask having a 90 relatively large end and a relatively small end, and being provided with a pair of opposite parallel sides and a pair of opposite converging sides, of a tapering flask likewise provided with a large end and a 95 small end, and having parallel outer faces received between the parallel sides of the first-named flask, said tapering flask comprising separable sections inclosing a mold cavity whose periphery lies substantially 100 in the plane of the meeting edges of adjacent sections, said tapering flask being engaged between its ends by the converging sides of the first-named flask, the small end of the tapering flask being closed and the 105 large end presenting an opening to the relatively large end of the first flask, said opening extending substantially across the width of the mold cavity.

2. A mold-containing flask comprising a 110 pan-shaped section having a rim, a ring-shaped section similar in outline to the rim, and a third section, said sections having projections and recesses to enable them to be fitted together, so that the ring-shaped 115 section will coincide with the rim, and the third section with the ring-shaped section, the rim and the ring-shaped section having registering recesses forming an aperture in the flask to admit molten material to the 120 mold-cavity, said aperture extending across substantially the width of the mold-cavity, the rim and the ring-shaped section having other registering recesses forming exit 125 openings, the bottom of the pan-shaped section and the third section also being provided with exit openings, said openings being located at various points with respect

to the mold-cavity, whereby a pressure agent may be applied through the aperture to force the molten material into the mold-cavity, and be subsequently enabled to escape from the flask.

In testimony whereof, I have signed my name to this specification, in the presence

of two subscribing witnesses, this 15th day of December, 1915.

LAKE H. SPRINKLE.
